UNITED STATES PATENT OFFICE.

EDWARD F. SIMPSON, JR., OF OAK LANE, PENNSYLVANIA, ASSIGNOR TO THE S. S. WHITE DENTAL MANUFACTURING COMPANY, OF PHILADELPHIA, PENNSYLVANIA, A CORPORATION OF PENNSYLVANIA.

DESIGN FOR A TOOL-HANDLE.

45,435.

Specification for Design.

Patented Mar. 17, 1914.

Application filed November 26, 1913. Serial No. 803,341. Term of patent 14 years.

To all whom it may concern:

Be it known that I, EDWARD F. SIMPSON, Jr., a citizen of the United States, residing at Oak Lane, county of Philadelphia, State of Pennsylvania, have invented a certain new, original, and ornamental Design for Tool-Handles, whereof the following is a specification, reference being had to the accompanying drawing.

In the accompanying drawing, Figure 1 is a perspective view of a handle embodying my design, shown in connection with a lance blade; Fig. 2 is a side elevation of the handle shown in Fig. 1; Fig. 3 is a plan view of said handle; Fig. 4 is an enlarged front elevational view of the handle and blade; Fig. 5 is an enlarged transverse sectional view taken through the neck between the blade and handle proper on the line 5—5 in Fig. 2; Fig. 6 is an enlarged transverse sectional view taken through the body of the handle on the line 6—6 in Fig. 2; and Fig. 7 is an enlarged transverse sectional view taken through the handle adjacent to its rear end on the line 7—7 in Fig. 2.

The essential characteristics of the design are embodied in a handle as above shown in Figs. 1, 2 and 6, having its maximum

girth at about one-third of the distance from its connection with the tool, or at about the region of the section 6—6 in Fig. 2, where the lateral edges of its substantially flat upper surface abruptly join the opposite convex side surfaces which converge downwardly and merge into the sharp curved lower edge. From this region of maximum girth said handle tapers forwardly toward the tool, which may be of any selected contour, to the restricted neck which connects said tool to the handle, and also tapers rearwardly from said region of maximum girth to its butt end, gradually changing from the contour shown in transverse section in Fig. 6 to the flattened oval contour shown in transverse section in Fig. 7.

I claim:

The ornamental design for tool handle substantially as shown and described.

In witness whereof, I have hereunto set my hand this 24th day of November, A. D., 1913.

EDWARD F. SIMPSON, JR.

Witnesses:

CLIFTON C. HALLOWELL,
HARRY R. BARBER.
